United States Patent Office

Des. 192,204
Patented Feb. 13, 1962

192,204

VEST

Lorena G. Bedient, Marshall, Wash. (Rte. 1, Spokane, Wash.), and Julia E. Mewes, 2511 N. Vista, Spokane, Wash., assignors of one-third to Ruth W. Dobson, Spokane, Wash.

Filed Feb. 24, 1961, Ser. No. 64,054

Term of patent 14 years

(Cl. D3—4)

FIG. 1 is a front view of a vest showing our new design. The broken line fragmentary showing of a shirt is for illustrative purposes only.

FIG. 2 is a rear view thereof.

We claim:

The ornamental design for a vest, as shown and described.
